HOLDER FOR A HAIR DRYER

Thomas M. West III, 206 W. Alton Ave.,
Santa Ana, Calif. 92707

Filed Aug. 25, 1975, Ser. No. 607,560

Term of patent 14 years

Int. Cl. D6—04

U.S. Cl. D6—125

FIG. 1 is a reduced perspective view of a holder for a hair dryer showing my new design;

FIG. 2 is a top plan view thereof;

FIG. 3 is a front elevational view thereof;

FIG. 4 is a bottom plan view thereof;

FIG. 5 is a side elevational view taken from the left of FIG. 3;

FIG. 6 is a rear elevational view thereof; and

FIG. 7 is a side elevational view taken from the right of FIG. 3.

I claim:

The ornamental design for a holder for a hair dryer, as shown and described.
